US00D931225S

(12) **United States Design Patent** (10) Patent No.: **US D931,225 S**
(45) Date of Patent: **** Sep. 21, 2021**

(54) **CONNECTOR**

- (71) Applicant: **Molex, LLC**, Lisle, IL (US)
(72) Inventors: **Lupco Zabjanovski**, Countryside, IL (US); **Robert Piszczor**, La Grange, IL (US); **Jeffrey J. Shrigley**, Wheaton, IL (US); **Michael A. Bandura**, Naperville, IL (US)
(73) Assignee: **Molex, LLC**, Lisle, IL (US)
(**) Term: **15 Years**
(21) Appl. No.: **29/708,361**
(22) Filed: **Oct. 4, 2019**
(51) LOC (13) Cl. **13-03**
(52) U.S. Cl. **USPC D13/147**
(58) **Field of Classification Search**
USPC D13/118, 123, 133, 146, 147, 153, 154, D13/156, 173, 184, 199

CLAIM

The ornamental design for a connector, as shown and described.

DESCRIPTION

FIG. 1 is a top front perspective view of a connector showing our new design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top front perspective view of an alternate embodiment of a connector showing our new design which is a mirror image of the connector of FIGS. 1-8;

FIG. 10 is a top rear perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The dash-dot broken lines immediately adjacent to the shaded areas depict the bounds of the claimed design and form no part thereof. The dash-dash broken lines depicting the remainder of the connector form no part of the claimed design.

1 Claim, 16 Drawing Sheets
